US0D1037142S

(12) **United States Design Patent** (10) Patent No.: **US D1,037,142 S**
(45) Date of Patent: ** Jul. 30, 2024

(54) **SET OF CORNERS OF A PORTABLE POWER DEVICE**

(71) Applicant: **Lion Energy, LLC**, American Fork, UT (US)

(72) Inventors: **Tyler Hortin**, American Fork, UT (US); **Thierry Caussat**, American Fork, UT (US); **Timothy Nelson**, American Fork, UT (US)

(73) Assignee: **Lion Energy, LLC**, American Fork, UT (US)

(**) Term: **15 Years**

(21) Appl. No.: **29/868,106**

(22) Filed: **Nov. 18, 2022**

(51) LOC (14) Cl. **13-02**

(52) U.S. Cl.

USPC **D13/103**

(58) **Field of Classification Search**

(57) **CLAIM**

We claim the ornamental design for a set of corners of a portable power device, as shown and described.

DESCRIPTION

FIG. 1 is a front perspective view of a set of corners of a portable power device of our new design;

FIG. 2 is a front view thereof;

FIG. 3 is a back view thereof;

FIG. 4 is a side view thereof;

FIG. 5 is an opposite side view thereof;

FIG. 6 is a top view thereof; and,

FIG. 7 is a bottom view thereof.

The broken lines in the drawing illustrate portions of the article that form no part of the claim.

1 Claim, 4 Drawing Sheets
